UNITED STATES PATENT OFFICE.

RUPERT GEORGE DAWSON, OF OVERDALE, DUNBLANE, SCOTLAND.

DESIGN FOR A GLASS BOTTLE.

48,813.

Specification for Design.

Patented Apr. 4, 1916.

Application filed November 13, 1914. Serial No. 872,019. Term of patent 14 years.

To all whom it may concern:

Be it known that I, RUPERT GEORGE DAWSON, a subject of the King of the United Kingdom of Great Britain and Ireland, residing at Overdale, Dunblane, Perthshire, Scotland, have invented a new, original, and ornamental Design for Glass Bottles, of which the following is a specification, reference being had to the accompanying drawings, forming part thereof.

Figure 1 is a side view of the bottle. Fig. 2 is a sectional view of part of the bottle and taken on the line A, A, Fig. 1.

The bottle is made with a body part B having a series of substantially circular in-

dentations C in the side thereof, such indentations being arranged at equal distances apart and extending right around the bottle with the exception of the portion D which is left plain so as to receive a label.

Claim:

The ornamental design for a glass bottle having a series of circular indentations extending around a portion of the body of the bottle as shown and described.

RUPERT GEORGE DAWSON.
